WALL AND CEILING COVERING.

No. 19,621.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,621, dated January 28, 1890.

Application filed December 26, 1889. Serial No. 335,052. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

The leading feature of my design consists of a central oblong panel 1, on which rests a two-handled urn 2, having on each side a branch of leaves 3 and 4 and ribbons 5. From two buttons 6 and 7 hang festoons of ribbons 8, 15 between which is a pendant 9. A festoon wreath hangs from each side of central panel 10 and 11.

At base of design rest two winged griffins 12 and 13, between which is a scroll-work upright 14.

There is a narrow molding at top of design 15, and a wider one at base divided into panels, some of which are ornamented with leaves 16 and others with spiral scrolls 17.

What I claim is—

The design for a wall and ceiling covering herein shown and described, consisting of panels, urn, wreaths, festoons, ribbons, rosettes, and griffins, with an upper and a lower border.

PAUL GROEBER.
